UNITED STATES PATENT OFFICE.

MICHAEL BLATT, OF NEW YORK, N. Y.

WICK FOR CANDLES.

SPECIFICATION forming part of Letters Patent No. 613,440, dated November 1, 1898.

Application filed March 5, 1897. Serial No. 626,123. (No model.)

To all whom it may concern.

Be it known that I, MICHAEL BLATT, a subject of the Emperor of Austria-Hungary, and a resident of New York city, in the State of 5 New York, have invented a new and useful Wick for Candles, of which the following is a specification.

My invention relates to an improvement in wicks for candles; and the object of my invention is to give wicks for candles durability, so that they may not be so readily consumed while the candle is burning.

I attain this object as follows: By twisting tightly around a piece of little broom-corn 5 straw of the desired length a piece of soft cotton thread, so as to completely envelop it,

and waxing the outside of the thread after being so wound around the straw, so as to hold it firmly in position.

This wick can be used either in paraffin; 20 lard, fat, or oil.

What I do claim as my invention is as follows:

A lamp-wick consisting of a broom-corn straw enveloped in a soft cotton thread twisted tightly around it, the thread being waxed on the outside whereby it is retained in position on the straw, substantially as specified.

MICHAEL BLATT.
